19 Claims. (Cl. 250—27.5)

1

This invention relates to electron discharge tubes of the hard vacuum tube type, and more particularly to triodes used in cross-magnetizing magnetic fields to provide large anode currents without grid losses for use in power amplifiers, oscillators, inverters, and the like.

In one type of hard vacuum triode, such as disclosed for example in our prior application, Ser. No. 726,382, February 4, 1947, conveniently termed a magnatriode, a number of filamentary thermionic emissive cathodes and elongated flat grid bars are disposed alternately in parallel relation between opposing anode surfaces in a strong magnetic field directed transversely of the cathodes, so that relatively high positive potentials may be applied to the grid bars to obtain large anode currents, without having the substantial electron current to the grid bars and the grid circuit losses characteristic of the conventional triode when operated with positive grid potentials.

The primary object of the present invention is to provide a tube structure of this magnatriode type, in which suitable areas for cathode emission and grid control for large anode currents may be obtained within over-all dimensions suitable for use in an efficient magnetic circuit, and in which the desired relatively close spaced relationship of the parts, with the necessary electrical isolation or insulation between the parts, may be readily obtained, and maintained under operating conditions of temperature and the like, in a simple structure easily fabricated and assembled.

Various other objects, attributes, and advantages of the invention will be in part apparent, and in part pointed out as the description progresses.

Generally speaking by way of explanation, and without attempting to define the nature and scope of the invention, it is proposed to support the ends of the grid bars and cathodes in such a type of tube by headers of steatite or like heat resistant insulating material, with adequate provision for allowing endwise expansion of these grid bars and cathodes under changes in temperature, and to utilize the anode for supporting and maintaining the headers and associated grid bars and cathodes in the proper space relation. It should be understood that various adaptations, modifications and additions may be made to the structural organization thus outlined in this explanatory statement without departing from the invention.

In the accompanying drawings, which illustrate one specific embodiment of the invention, Fig. 1 is a general view showing in outline one

2

typical application of the tube structure of this invention using a permanent magnet for providing the cross-magnetizing field.

Fig. 2 illustrates schematically for explanatory purposes a transverse section through what may be termed an elemental unit of the magnatriode type of tube, which constitutes the basis of the tube structure of this invention.

Fig. 3 is one view of the general organization of 10 the tube of this invention, in the form of a longitudinal section through the tube, with part of the anode removed.

Fig. 4 is another longitudinal section through 15 the tube in another plane along the line indicated at 4—4 in Fig. 3.

Figs. 5 and 6 are two transverse sections 20 through the tube along the lines 5—5 and 6—6 respectively in Fig. 3.

Figs. 7, 8 and 9 are fragmentary enlarged views 25 illustrating certain details of the mounting end support for the cathodes and grid bars characteristic of this invention.

Before describing in detail the particular embodiment of the invention shown, it would appear 30 to be expedient to outline briefly the purposes and functions of this magnatriode type of tube, and some of the problems involved in providing a suitable tube structure of this kind. For this purpose there is shown schematically in Fig. 2

35 a transverse section through the cathode, grid bars and anodes of what may be termed an elemental unit of this type of tube, which is developed or expanded in the tube structure of this invention. Referring to Fig. 2, the thermionic

emissive cathode C is of the elongated or filamentary type, and is disposed between and at substantially equal distances from two anodes or plates A and A¹, and two flat grid bars G and G¹, in the manner indicated in Fig. 2. The cathode

40 C, grid bars G, G¹, and anodes A, A¹ which are shown in cross section in Fig. 2, are assumed to be extended to an appropriate length. This arrangement of tube elements, enclosed within a suitable evacuated envelope (not shown in Fig. 2),

45 is disposed in a strong uni-directional magnetic field between the pole pieces designated N and S of a permanent magnet, or equivalent source of magneto-motive-force. The magnetic lines of force through the tube act in the direction indicated by the arrow H substantially at right angles to the surfaces of the anodes A, A¹ and parallel with the surfaces of the grid bars G, G¹.

In this elemental magnatriode unit shown in Fig. 2, it can be seen that the potential on the grid bars G, G¹ will act to control or modify the

potential gradient to the emissive surface of the cathode C as provided by the space charge and anode voltage, and thus govern the anode current in much the same way as if the grid were located in the direct path for electron movement from the cathode to the anode, as in the conventional triode. The magnetic field acting in the direction indicated by the arrow H, and constituting a cross-magnetizing field with respect to the cathode C, may be said to act, in accordance with well known principles relating to the movement of electrons in a magnetic field, to converge or focus the electrons leaving the cathode C into beams or streams, such as indicated by dotted lines 5 in Fig. 2. Assuming the appropriate strength of magnetic field with respect to the spacing of the tube elements and voltages involved, a relatively high positive potential may be applied to the grid bars G, G¹ to neutralize the space charge and obtain large anode currents, without having appreciable electron current to these grid bars, since the effect of the magnetic field is to confine the electrons coming from the cathode to paths which do not touch the grid bars. This and other operating characteristics of the magnatriode type of tube, as exemplified in the elemental unit shown in Fig. 2, enable such a tube to be advantageously employed in various types of circuit organizations suitable for conventional triodes, such as amplifiers, oscillators, control rectifiers, inverters and the like; but since such applications and uses of this type of tube are not material to the present invention and form the subject matter of other applications, it is unnecessary to discuss further the operating characteristics and advantages of the magnatriode type of tube. Also, this type of tube is disclosed and claimed in other applications, such as our prior application above mentioned; and no claim is made herein to the basic features, functions and structures disclosed in these other applications.

Generally speaking, the tube structure of this invention involves a unitary assembly of a number of elemental tube units shown in Fig. 2 side by side, in such a manner as to establish and maintain under operating conditions the desirable relatively close space relation between the tube elements in an isolated or insulated relation. In providing such a tube structure, among other things it is desirable to provide a compact assemblage within over-all dimensions suitable for disposition of the tube in a short airgap of a magnetic circuit, so that a strong magnetic field through the tube is obtained for the size of permanent magnet or equivalent source of magneto-motive-force employed. During operation of the tube the various parts of such a compact assembly tend to assume high and somewhat variable temperatures; and in supporting cathodes and grid bars in their relatively close relationship to each other and the anode surfaces, it is necessary to make provision for their expansion under changes of temperature without materially disturbing this space relationship. Also, in this type of tube, the heating current through the cathodes creates a magnetic field which reacts with the strong magnetic field in which the tube is disposed in a way to exert a sidewise bending or displacing force upon the cathode, as later described; and in order to limit the effects of such motor action, it is desirable to provide, in addition to using a cross section for the cathodes suitable for resisting such bending force, a form of support for these cathodes which

will exert an endwise pull thereon when heated. The structural organization characteristic of this invention satisfies these and other requirements or conditions for the magnatriode type of tube in a simple and effective manner.

Considering now the specific embodiment of the invention illustrated in the accompanying drawings, it is assumed that the tube will be disposed in the airgap of a permanent magnet; and as a typical example of such an application of the tube, Fig. 1 shows in outline a tube T in connection with one form of a permanent magnet. In the particular arrangement shown, which of course is merely typical and is susceptible to various modifications, the permanent magnet comprises two curved arms 6, assumed to be circular in cross section, formed of a permanent magnet material, such as the alloy commonly known as Alnico. The lower ends of these curved arms 6 are attached to a soft iron back yoke or base 7 in a suitable manner, such as by screws (not shown) threaded into inserts in the ends of these arms. Soft iron pole pieces 8 of a general rectangular shape are fastened in a similar manner to the upper ends of the arms 6 of the permanent magnet, these pole pieces being parallel and providing an airgap as small as the dimensions of the tube T will permit. The grid bars and anode are disposed in the envelope of the tube T, so that when the tube T is in place, as shown in Fig. 1, the magnetic lines of force act in a direction with relation to these grid bars and anode, as indicated in Fig. 2. As illustrated in Fig. 1, it is assumed that the tube T will be supported in an upright position by a suitable base and socket, generally indicated in outline at 9, mounted on the back yoke 7 of the magnet. The arrangement shown in Fig. 1 is merely representative of the various ways in which the tube structure of this invention may be associated with a magnetic circuit; and it is contemplated that various expedients in the way of forced draft air cooling or immersion in oil may be employed for heat dissipation as required.

In order that the tube may be employed in the short airgap of an efficient magnetic circuit, such as between the pole pieces of the permanent magnet in Fig. 1, it is desirable that the tube should be relatively thin or narrow in thickness to fit in a short airgap between such pole pieces, which may be enlarged to cover the length of the tube appropriate to the strength of the filamentary cathode and a width conforming with the number and spacing of grid bars being employed in the particular tube structure. Accordingly, the tube elements are arranged and disposed within a tube envelope which is relatively thin in thickness as compared with its breadth and width. In the embodiment of the invention shown, this tube envelope E is assumed to be of glass, and to have walls which are straight longitudinally of the tube, but curved transversely to have a general elliptical cross section, as shown in Figs. 5 and 6, so that the walls of this envelope will have the necessary strength to resist pressure when exhausted. The tube elements are supported in a press 12 formed at the lower end of the envelope E in the usual manner; and the envelope is provided with a tubulation, at the other end, such as indicated at 13, for exhaust purposes.

The assembly of tube elements comprises a number of narrow elongated grid bars G in substantially equally spaced parallel relation and filamentary cathodes C arranged alternately in

a multicellular box-like assembly, which is located inside of a hollow sheet metal anode A of rectangular cross section, with the grid bars disposed edgewise to opposing anode surfaces. The typical arrangement shown comprises seven grid bars G and six cathodes C.

The anode A is formed from sheet stock of a suitable non-magnetic material, such as tantalum, molybdenum, or the like, in two halves having flanges 15 which are welded together as shown in Fig. 5, so as to form a hollow box or tube of rectangular cross section. This anode A is supported by two rods 16 welded to its narrow sides which are anchored to lead-in supports 17 extending through seals in the press 12 of the envelope, to constitute a rigid support for the anode A and also provide external connections for the anode circuit. The anode A is slotted or notched near the corners at both ends, so that edge portions along the ends of the wide sides may be bent in slightly, as shown in Fig. 4, to constitute lips 19 to cooperate with the insulator cathode headers, as later described. The anode A may be provided with corrugations or ribs (not shown) for longitudinal and lateral stiffness, if desired. It may be pointed out that an anode A of a closed tubular form is preferably employed, so that it may be more readily heated for out-gassing it by induction heating or bombing procedure in accordance with the usual practice.

The grid bars G and the cathodes C are supported at their ends by upper and lower supporting elements or headers 21, 22 of a heat resistant insulating material, preferably one of the ceramic materials, such as commonly known as steatite. These headers have a cross section, such as indicated in Fig. 7, to have the necessary lateral stiffness and have a ledge or shoulder 24 along their longitudinal edges to be engaged by the bent-in edges or lips 19 of the anode. The same header as shown in Fig. 7 for the upper end of the tube is turned upside down for the lower header 22. In other words, the insulator headers 21, 22 are held apart in a predetermined space relation by the engagement of the lips 19 at the ends of the anode A with the shoulders 24 on these headers.

The upper and lower headers 21, 22 are each formed with transverse slots 25 to receive the ends of the grid bars G, as shown in Figs. 7 and 8. These grid bars G are flat, narrow, elongated strips and are fitted into the slots 25 of the headers 21, 22 with a small clearance to prevent binding, but permitting endwise movement of these grid bars when expanded lengthwise under temperature changes. The grid bars G are held in place in the upper header 21 after assembly by a small rod or wire 26 welded to one edge of these grid bars and resting on a ledge of the insulator header, as shown in Figs. 4 and 7. The grid bars G at their lower ends have a similar rod 27 welded to their edges (see Fig. 3), which in turn is bent and welded to a grid lead-in support 28, sealed in the press 12 of the envelope, to afford an external electrical connection to the grid bars G, as can be readily understood.

The grid bars G are preferably of such a length that they do not extend the full depth of the slots 25 in the insulator headers 21, 22; and these slots 25 are also preferably made somewhat wider for a portion of their depth than the thickness of these grid bars, as best shown in Fig. 8, so that the slots afford additional surfaces to increase the distance for surface leakage over the insulator headers between the grid bars and the ad-

jacent cathodes, which are disposed between these grid bars in a manner later described. Also, the vertical portions of such leakage surface adjacent a grid bar are closely spaced thereto, so as to be shielded from condensation of evaporated materials coming from the cathodes and other tube elements during the out-gassing and exhaust procedure. A similar protected creepage surface is provided for each of the cathodes, as later pointed out. In this connection, it can be appreciated that the accumulation of evaporants on exposed surfaces of the insulator headers 21, 22 tends to reduce the resistance between the electrodes supported by these headers, and impose limitations upon the voltages between electrodes that can be satisfactorily employed, so that it is important to increase the leakage paths between the electrodes and shield some of the surfaces of these insulators from condensation of evaporants.

The grid bars G are made of a non-magnetic metal suitable for use in hard vacuum tubes at the temperatures involved. Tantalum, molybdenum, Nichrome and similar metals are generally suitable for this purpose; and for some types of tubes, it is desirable to provide surface oxidation or other surface treatment for the grid bars G to reduce their tendency to become emissive at the temperatures they acquire in the compact assembly characteristic of this invention for tubes of the higher ratings.

The cathodes C are of the elongated or filamentary form, and may be tungsten, thoriated tungsten, or of the oxide coated type, as best suited for the rating and operating requirements of the tube. As shown in Figs. 3 to 9 it is assumed that the cathodes C comprise a nickel tube 31 as a core (see Figs. 7 and 8) and have formed thereon an oxide coating, indicated in an exaggerated manner at 32, which may be formed in accordance with the disclosure of the prior patent to D. V. Edwards et al., No. 1,985,855, dated December 25, 1934. A tube of circular or oval cross section represents a simple and convenient way of providing a distribution of metal for the cathodes in a cross section adapted to resist the sidewise bending force of what may be termed motor action characteristic of this type of tube. Considering this motor action effect, and referring to the elemental tube unit of Fig. 2, it can be seen that the cathode C, when carrying heating current, is in effect a wire carrying current disposed in a magnetic field acting in the direction indicated by the arrow H; and in the same way that any wire carrying current in a magnetic field has a force exerted thereon, the cathode C is subjected to a force tending to move it sidewise with respect to the direction of the magnetic field indicated by the arrow H, in one direction or the other dependent upon the direction of the current flowing in the cathode C with respect to the polarity of the magnetic field. This force of motor action tends to vary the distance between the grid bars and the cathode for different parts of its length, and thus interfere with the control and operating characteristics of the tube. Also, if alternating current is used for heating the cathode C, as is usually most convenient, this motor action tends to vibrate the cathode and cause failure on account of metal fatigue. Consequently, it is desirable to employ a cross section for the cathode, such as the tubular arrangement assumed, which will resist to the best advantage this sidewise bending force. It should be understood, however, that an oxide coated

tubular cathode as illustrated in Figs. 7 and 8 is merely typical, and it is contemplated that oxide coated cathodes of other cross sections, such as channel shaped, rectangular, or the like, may be employed. Further, the cathode may be a strip 34 of tungsten or thoriated tungsten disposed edgewise to the grid bars G, as indicated in the modification of Fig. 9. When a strip of tungsten is used, as in the modification of Fig. 9, it is preferable to provide an end connector of good heat conductivity, such as indicated at 35 in Fig. 9, to which the tungsten strip 34 is welded, since the emission temperature for tungsten is high as compared with what the insulator headers 21, 22 are adapted to withstand and it is desirable to use a connector operating at a lower temperature for direct contact with these insulator headers.

The cathodes C, in a spaced parallel relation to the grid bars G, as shown in Figs. 3 and 5, are supported by the upper and lower insulator headers 21, 22, in a manner to permit endwise expansion of the cathodes, and preferably with means for exerting an endwise pull on these cathodes individually after they are heated. In the particular construction illustrated, the cathodes C at their upper ends extend with a close but slideable fit through spaced holes 38 in the upper header 21, said holes being preferably enlarged for a portion of their length, as best shown in Fig. 8, to increase the distance for surface leakage between each cathode and the adjacent grid bars. The extreme upper end portions of the cathodes C are flattened and extend through holes in a somewhat flexible cross member or plate 39; and each cathode is attached to this plate by a small angle bracket 40 welded to the flattened end portion of the cathode and the cross member 39. A resilient element, in the form of a compression coil spring 42 around each end of the cathode is interposed between the cross member 39, to which the cathodes are attached, and the top of the upper header 21. These springs 42 may be made of tungsten, molybdenum, or similar material, and after being loosely wound in a spiral, are preferably subjected to a preliminary baking and out-gassing procedure in vacuum, after which they are compressed to provide the appropriate tension prior to assembly in the tube. Springs of other suitable material, or other forms of resilient elements may be used.

The lower ends of the cathodes C extend through spaced holes in the bottom insulator header 22; and half of the cathodes, three as shown, have their end portions flattened and welded to one cross bar 45 attached to a cathode support and lead-in rod 46 sealed in the press 42 in the envelope; and the other half of these cathodes are welded in a similar manner to another cross bar 47 attached to a similar cathode support and lead-in rod 48. It can be seen that the heating current supplied to the cathode lead-in rods 46, 48 will flow in one direction through three of the cathodes in multiple to the top of cross member 39, and in the other direction through the other three cathodes in multiple.

Various procedures may be followed for assembly of this tube structure. For oxide coated cathodes, such as assumed for the structure shown in Figs. 3 to 8, it is preferable to assemble the nickel tubes 31 for these cathodes in the insulator headers 21, 22, while held apart in the proper space relation by some suitable detachable spacing clamp, apply and treat the oxide coating, and then insert the grid bars G in the slots 25 in the insulator headers 21, 22 from the

bottom, welding the rods or wires 26, 27 to the edges of these grid bars to hold them in place. After this partial assembly, the anode A is substituted for the temporary spacing device being used. The complete assembly may then be inserted in the envelope E, and the press 42 formed in the regular way to hold the assembly of tube elements in position.

It is assumed that, after the tube elements have been mounted in the envelope, the appropriate procedure will be followed to activate the cathodes and thoroughly out-gas all of the parts, connecting the envelope E to the vacuum system by the tubulation 13 during this operation. No unusual or special exhaust or out-gassing procedure is required for the tube structure of this invention, other than employed for ordinary hard vacuum tubes in accordance with established practice. It is contemplated that the envelope will be fully exhausted to eliminate as far as practical all traces of air or gas. It is generally preferable to use metals such as molybdenum, tantalum, tungsten or perhaps Nichrome for the various tube elements and supports, on account of their non-magnetic qualities needed to avoid distortion of the magnetic field characteristic of this type of tube. It should be understood, however, that there is considerable choice in the materials that can be used successfully for the electrodes, supporting elements and insulators of the tube structure of this invention; and it is not intended to limit this invention to any particular type or combination of materials.

From the foregoing, it can be appreciated that the organization or assembly of parts characteristic of this invention provides a compact unitary assembly of the component elements for a tube of this type in the appropriate over-all dimensions and with such relatively close spacing of cathodes, grid bars and anodes, as may be desirable for certain tube characteristics. The grid bars G may expand endwise when heated without being warped or bent. The cathode C are so mounted that they may readily expand lengthwise when heated; and in addition to having a cross section suitable for resisting the force of motor action characteristic of this type of tube, are subjected to an endwise tension or pull, which keeps these cathodes straight and in the proper space relation to the grid bars and anodes, and tends to prevent sidewise bending or displacement of the cathodes by any twisting or warping action of the force of motor action, that might otherwise with the limited amount of metal available for the cross section of the cathode permit such bending distortion. The anode A itself supports the insulator headers 21, 22 carrying the grid bars and cathodes, thereby providing a predetermined relationship between the parts independently of the means supporting the tube elements in the envelope. Incidentally, the endwise expansion of the anode A when heated compensates to some extent for the expansion of the grid bars and cathodes. The insulator headers 21, 22 are disposed largely outside of the anode A, and hence, together with the springs 42 wholly outside of the anode A, tend to assume a low temperature as compared with the other parts enclosed within the anode.

Obviously, the same general organization shown may be employed to provide as few or as many of the elemental tube units of Fig. 2 as may be expedient. In this connection, the spacing between the grid bars G and the cathodes C is determined by the insulator headers 21, 22; and

since these headers are made of steatite or equivalent insulating material, which does not expand materially with changes in temperature, a relatively large number of grid bars and cathodes may be employed, without causing their space relationship to be changed by expansion under operating temperatures, as in the case where metallic elements are used to support the ends of the grid bars and cathodes and determine their space relation.

The specific tube structure shown and described will serve to illustrate the nature of the invention as exemplified in one specific embodiment; but it should be understood that various adaptations, modifications, and additions may be made to the particular structure illustrated without departing from the invention.

What we claim is:

1. An electron discharge tube for use in a cross-magnetizing field comprising in combination with an envelope having substantial breadth and width with respect to its thickness for disposition in the short airgap of a magnetic circuit, a multicellular assemblage of grid bars and filamentary cathodes arranged alternately in parallel relation between opposing parallel anode surfaces, said grid bars being disposed edgewise to said opposing flat surfaces of the anode, means including insulators of ceramic material supporting said grid bars and cathodes wholly from said anode in a predetermined space relation to each other and to said anode surfaces, and means supporting said assembly of grid bars, cathodes and anode in said envelope.

2. An electron discharge tube for use in a cross-magnetizing field comprising in combination, a pair of narrow elongated headers of heat resistant insulating material, a plurality of narrow elongated grid bars slidably supported at their ends in spaced slots in said headers, a plurality of filamentary thermionic emissive cathodes supported by said headers in parallel relation with said grid bars, one cathode between each pair of grid bars, and an elongated hollow sheet metal anode around said grid bars and cathodes, said headers of insulating material being supported and held apart in a predetermined space relation wholly by said anode.

3. A hard vacuum triode comprising in combination, an envelope relatively long and wide with respect to its thickness, and a unitary multicellular assembly of alternate elongated grid bars and filamentary cathodes in parallel relation between opposing flat anode surfaces disposed in said envelope, said assembly including headers of heat resistant insulating material wholly supported by the anode for supporting the grid bars and cathodes and for permitting endwise expansion thereof individually.

4. An electron discharge tube comprising in combination, a plurality of narrow elongated flat grid bars and filamentary thermionic emissive cathodes disposed alternately in parallel relation, a pair of long headers of insulating and heat resistant material supporting said grid bars and cathodes at their ends and permitting endwise expansion individually, and an anode outside said grid bars and cathodes and including opposing flat surfaces in planes substantially at right angles to the planes of said grid bars, said anode supporting said headers in a predetermined spaced relation to each other and to said anode.

5. An electron discharge tube comprising in combination, a hollow sheet metal anode of rectangular cross section, a pair of spaced headers

of ceramic material supported by said anode at its ends, and a plurality of elongated grid bars and filamentary cathodes arranged alternately in parallel relation and wholly supported by said headers, said headers supporting said grid bars and cathodes to permit individual endwise expansion thereof while insulating them from each other and from the anode.

6. An electron discharge tube comprising in combination, an envelope of substantial breadth and width with respect to its thickness, an anode having two opposing spaced parallel surfaces supported within said envelope, a multicellular assembly of elongated flat grid bars and filamentary cathodes disposed alternately in parallel relation between the opposing surfaces of said anode, said grids being in planes essentially at right angles to the planes of said anode surfaces, and means including blocks of ceramic insulating material wholly supported by said anode for supporting said grid bars and cathodes in a predetermined space relationship to each other and to said anode surfaces.

7. A controllable electron discharge tube structure, comprising in combination with a pair of supporting headers of a ceramic insulating material, a plurality of filamentary thermionic emissive cathodes supported at their ends by said headers in a spaced parallel relation in a common plane, and means associated with said cathodes and said headers for permitting individual endwise expansion of said cathodes with respect to said headers and for maintaining an endwise pull on said cathodes individually after being heated under the operating conditions for the tube.

8. A hard vacuum tube comprising, in combination with an anode having two flat walls in spaced parallel relation, a pair of blocks of a ceramic insulating material at the ends of said anode walls and wholly supported thereby, a plurality of alternately arranged elongated flat grid bars and filamentary cathodes between said anode walls, said grid bars and cathodes being supported by said insulating blocks in a substantially equally spaced parallel relation, means electrically connecting said grid bars together, and means electrically connecting said cathodes for flow of heating current therein in opposite directions.

9. An electron discharge tube for use in a cross-magnetizing field comprising in combination, a tubular sheet metal anode of a substantially rectangular cross section, a pair of headers of a ceramic insulating material wholly supported by the ends of said anode, and a multicellular assembly of alternate elongated flat grid bars and filamentary cathodes supported by said headers within said anode, said grid bars being disposed in planes substantially at right angles to opposing surfaces of the anode.

10. An electron discharge tube structure comprising in combination, an anode having parallel opposing surfaces, insulator headers of steatite wholly supported by said anode, a plurality of elongated flat grid bars supported for endwise sliding movement in slots in said headers, said grid bars being disposed edgewise to said anode surfaces, and a plurality of filamentary thermionic emissive cathodes supported by said headers one between each adjacent pair of grid bars.

11. A hard vacuum triode for use in a cross-magnetizing field comprising in combination, a pair of headers of rigid insulating material having substantially equally spaced slots and holes therein, a plurality of narrow elongated grid bars

11

slidably supported at their ends in the slots of said headers, a plurality of filamentary thermionic emissive cathodes supported in said holes of said headers between said grid bars, and an anode having opposing surfaces opposite the edges of said grid bars for supporting and maintaining said headers in a predetermined space relation.

12. A cathode structure for a hard vacuum triode comprising in combination, a pair of spaced blocks of ceramic material constituting cathode headers and having a plurality of spaced holes therein, a plurality of filamentary thermionic emissive cathodes disposed in essentially equally spaced parallel relation in a common plane, said cathodes extending at their ends through said holes, means electrically connecting all of said cathodes together to one end, and separate means electrically connecting together different groups of said cathodes at the other end, whereby the heating current passes in one direction through one group of cathodes and in the opposite direction through the other group.

13. A hard vacuum triode comprising in combination with a plurality of narrow elongated flat grid bars, of a pair of supporting headers for supporting said grid bars at their ends in equally spaced parallel relation, said headers being of a ceramic insulating material and having spaced slots therein to slidably receive the ends of said grid bars.

14. A grid supporting structure for electron discharge tubes comprising in combination, a pair of blocks of ceramic heat resistant material having equally spaced slots therein, a plurality of elongated grid bars slidably fitting at their ends in said slots, and means welded to the edges of said grid bars for electrically connecting them and holding them together in place in the slots of said blocks.

15. A cathode structure for electron discharge tubes comprising in combination, a pair of insulator headers of a rigid heat resistant insulating material having spaced holes therein, a plurality of filamentary cathodes extending at their ends through said holes, and individual resilient elements for said cathodes cooperating with one of said headers to exert an endwise pull on the corresponding cathode when heated.

16. A controllable electron discharge tube structure comprising, in combination with a plurality of filamentary cathodes disposed in a spaced parallel relation in a common plane, a pair of insulator headers of a rigid heat resistance insulating

12

material having spaced holes therein, said cathodes extending at their ends through the holes in said headers, and means including a flexible member for electrically connecting said cathodes together at one end.

17. An electron discharge tube comprising, in combination with an insulator header of ceramic material having a plurality of equally spaced holes therein in a common plane, a plurality of cathodes extending at their ends through said header, said cathodes having a cross-section resisting sidewise bending in parallel planes, and means including resilient elements cooperating with said header for electrically connecting said cathodes together and exerting an endwise pull on said cathodes.

18. A cathode structure for electron discharge tubes comprising in combination, a block of heat resistant insulating material of a ceramic nature constituting a cathode supporting element and having a plurality of equally spaced holes therein in a common plane, a plurality of filamentary cathodes extending at their ends through said holes in said header, a flexible cross member connected to the ends of said cathodes, and a resilient element for each cathode interposed between said header and said cross member.

19. An electrode assembly for hard vacuum electron discharge tubes comprising in combination, a pair of headers of insulating and heat resistant material, and a plurality of elongated grid bars and filamentary cathodes arranged alternately in parallel relation, each of said headers having therein a row of substantially equally spaced openings to receive the ends of said grid bars and cathodes, said openings for part of their depth being somewhat larger than the cross section of the corresponding grid bar or cathode therein, thereby providing a recess in said headers around each grid bar and cathode to prevent the formation of a continuous conductive surface leakage path by the accumulation of evacuated material.
